UNITED STATES PATENT OFFICE.

EDWARD F. FLETCHER, OF SHREWSBURY, MASSACHUSETTS, ASSIGNOR TO WORCESTER BRUSH & SCRAPER COMPANY, OF WORCESTER, MASSACHUSETTS, A CORPORATION OF MASSACHUSETTS.

FLOOR BRUSH.

Application filed December 29, 1920. Serial No. 433,754.

To all whom it may concern:

Be it known that I, EDWARD F. FLETCHER, a citizen of the United States, residing at Shrewsbury, in the county of Worcester and 5 State of Massachusetts, have invented a new and useful Floor Brush, of which the following is a specification.

This invention relates to a metallic brush for sweeping floors, particularly rough floors 10 in garages, machine shops and factories that are likely to be covered with grease and metal chips or turnings.

The principal objects of the invention are to provide means whereby the operative surface 15 of the brush can be formed of a series of brush units constructed in accordance with the patent to Gilbert C. Bemis, #1,100,113, patented June 16, 1914, and to provide a convenient and practicable means for detachably holding them in position; also to provide a convenient construction for holding the handle on the brush back, in proper position to operate the brush or a scraper on the back.

25 Further objects and advantages of the invention will appear hereinafter.

Reference is to be had with the accompanying drawing in which—

Fig. 1 is a perspective view of a floor brush 30 constructed in accordance with this invention;

Fig. 2 is a transverse sectional view of the same showing one of the brush elements omitted to illustrate the construction of the 35 holding elements;

Fig. 3 is a perspective view of one of the brush elements;

Fig. 4 is a sectional view of the same; and

Fig. 5 is a sectional view of the metallic 40 shell before the brush is applied.

In the above mentioned patent has been shown the construction of brush elements or tufts of wire bristles in which a metallic cylindrical shell 10 is provided with a series 45 of straight stiff wire bristles 11 arranged annularly on the inside of the shell. They are held in position by a wooden plug 12 driven in and by crimping or creasing the shell circumferentially against the bristles to form 50 a peripheral compression 13. Each of these tufts constitutes a brush element complete in itself.

In the present form I have illustrated this brush tuft as provided with an outwardly 55 extending flange 14 circular in shape and

in a plane substantially coincident with the end of the wooden plug 12. The tuft therefore is flat on this end and I make use of that for holding it in position in the following way.

The brush back consists of two pieces 15 and 16 preferably of wood. The lower one 15 is provided with a series of perforations 17 therethrough and these are counterbored at 18. These are made so that the cylindrical shell 10 will fit frictionally therein and the flange 14 will be received in the counterbore 18 and exactly fill it. The brush elements or tufts having all been inserted in the board 15, their opposite circular ends will all lie in the same circular plane and the flanges 14 will be flush with the upper surface of the board 15. These parts having been assembled as stated, the upper half 16 of the brush back, which is plain on the bottom, is applied 70 to the lower half and secured in position thereon as by screws 19. It will be seen therefore that the lower surface of this half of the back rests against the end surfaces of the flanges 14 and holds them firmly in position. 80 Thus, by simply screwing these two parts together, the brush elements are firmly anchored in position and no individual fastening devices have to be employed. But they are individually detachable by removing the 85 upper back section.

The upper section 16 of the brush back is provided on its front surface with a scraper 20 projecting forwardly therefrom, the edge thereof being sharpened as indicated. When 90 used for scraping purposes the brush is reversed as will be obvious.

I have shown the handle 21 as being secured in a cylindrical socket 22 in a cast member 23. This has a flat flange at an 95 angle to the axis of the socket secured as by screws to a flat projection 24 at the center of the upper half 16 of the brush back. It also has a flange at right angles thereto that engages the rear vertical edge of the back. 100 This casting is so located that the handle extends upwardly at a convenient angle to the brush back when the bottom surface of the brush is horizontal. Furthermore, the angle is of such a degree that when the device is 105 employed conveniently, the operator lowering it somewhat for this purpose.

From the above description it will be seen that the formation of the tufts or brush ele- 110

ments as shown in Fig. 3 constitutes the principal operation of making the brush. These elements can be made and assembled conveniently by machinery and are employed for other purposes so that they can be made in large numbers and under conditions of quantity production. These having been made, the production of the brush is very simple. The tufts are inserted 5 through the perforations in the lower member 15 and the flanges pressed to position in the counterbored openings. No special care has to be taken as to their location as it is almost impossible to get them in inaccurate 10 position. Even if not pressed home when first put in, they will be when the upper section 16 is applied and forced down by the screws. This constitutes an extremely simple and easy way for assembling 15 a brush and one that results in producing brushes of uniform construction. The brush is particularly valuable for use in sweeping rough floors, apt to have grease and particles of metal upon them. It will be seen 20 that the operative surface of the brush is made up of a plurality of circles of bristle ends spaced apart and having enough resiliency to enable them to retain substantially their original position and condition 25 even after rough usage. Whenever anything is encountered on the floor so hard that it cannot be taken up by these steel bristles the scraper is resorted to.

It will be observed that the brush elements 30 are firmly anchored in position and that the flanges 18 are in sockets so that they cannot descend below the point at which they are supposed to be located and they are prevented from moving even 35 slightly in the opposite direction by the upper brush back 16. Thus the operative ends of the bristles are all located in the same plane if originally made alike. Furthermore no special accuracy has to be ob- 40

served in the location of the parts, particu- 45 larly the two halves 15 and 16 for they would perform all their functions equally well even if misplaced a little. Such misplacement will not injure the brush in any 50 way, not even its appearance because the edge can be smoothed off by machinery after the two parts 15 and 16 are assembled. If the brush elements or tufts get worn out 55 they can be replaced either in whole or in part in a very simple way. By placing the scraper 20 in such position that it is in a

plane substantially at right angles to the axis of the handle and socket 22 it is suitably located for operation and is out of the way when the brush is used for brushing 60 purposes. By providing a series of hollow circles of stiff steel bristles spaced from each other the brush is rendered particularly desirable for the rough usage indicated because each tuft of bristles has two 65 separated surfaces, so to speak, which bristles sweep the floor when it is drawn along. There is also sufficient space in front of these surfaces to hold any ordinary material which may collect from the sweeping 70 operation.

Although I have illustrated and described only a single form of the invention I am aware of the fact that modifications can be made therein by any person skilled in the 75 art without departing from the scope of the invention as expressed in the claims. Therefore I do not wish to be limited to all the details of construction herein shown and described, but what I do claim is:

1. As an article of manufacture, a brush comprising a back having a lower member provided with perforations therethrough, counter-sunk at the top, a brush element in each perforation comprising a cylindrical 85 metallic bristle carrying shell open at both ends fitting the perforation and having an outwardly extending flat circular projection around its top located in the counterbores in the perforations, and an upper member 90 having a flat surface engaging the upper surfaces of the first named member and the ends of said shells to hold them firmly in position in said counterbores.

2. In a device of the character described, 95 the combination of a brush head, a plate fitting upon and conforming to the trans- 100 verse contour of the upper face of the brush head and fastened thereto, and having on its top a central projection, a member on the projection on said plate provided with a handle receiving opening adjacent its rear edge and having a flange leading over the rear edge of the plate, and fastened to the plate upon the brush head, a handle pro- 105 jecting into said opening, and a socket ex- tending from said member at the opening formed therein and fitting about the handle.

In testimony whereof I have hereunto affixed my signature.

EDWARD F. FLETCHER.
